UNITED STATES PATENT OFFICE.

OLIVER McCARTHY, OF MERIDEN, CONNECTICUT, ASSIGNOR TO THE MERIDEN BRITANNIA COMPANY, OF SAME PLACE.

DESIGN FOR A COFFIN-TRIMMING.

SPECIFICATION forming part of Design No. 16,782, dated July 6, 1886.

Application filed June 7, 1886. Serial No. 204,430. Term of patent 14 years.

To all whom it may concern:

Be it known that I, OLIVER McCARTHY, of Meriden, in the county of New Haven and State of Connecticut, have invented a new 5 Design for Coffin-Trimming; and I do hereby declare the following, when taken in connection with accompanying drawings and the letters of reference marked thereon, to be a full, clear, and exact description of the same, and to which said drawings constitute part of this specification, and represent, in—

Figure 1, a front view of the handle-socket; Fig. 2, a face view of a coffin-plate; Fig. 3, an end view of both alike.

15 This invention relates to a design for coffin-trimmings, with special reference to the handle-socket, plate, and other parts which are made of corresponding shape; and it consists in the representation of a flat plain plate resting upon a quilted cushion, as shown in the 20 accompanying illustration, and hereinafter described.

The plain surface A of the handle-socket, Fig. 1, or of the plate, Fig. 2, is in the form

of substantially a parallelogram. This surface is flat, and represents a flat plate. Around the edge of the flat plate is a border, rounded from the flat surface outward and backward, as seen in Fig. 3. This rounded surface or border is crossed by depressed lines representing stiches, and giving to the border the appearance of being quilted, and to the whole design the appearance of a flat plate resting upon a quilted cushion. 25

I claim—

30 The design for coffin-trimmings, consisting of the representation of a flat plate with a surrounding border rounded from the edge of the plate outward and backward, the rounded surface crossed by depressed lines representing stitching and giving the appearance of a 35 plate resting upon a quilted cushion, as described, and shown in the accompanying illustration. 40
